COUNTING AND PACKAGING MACHINE FOR
'CAPSULES OR THE LIKE'

Leland H. Merrill, 1243 W. Belmont Ave., Chicago, Ill.

Filed May 6, 1959, Ser. No. 55,789

Term of patent 14 years

(Cl. D55—1)

FIG. 1

FIG. 2

FIG. 1 is a rear perspective view of a counting and packaging machine for capsules or the like, embodying my new design; and

FIG. 2 is a front perspective view thereof.

The undisclosed side is substantially like the side shown.

I claim:

The ornamental design for a counting and packaging machine for capsules or the like, as shown and described.
